Specification for Design.

Patented June 12, 1917.

Application filed May 4, 1917. Serial No. 166,483. Term of patent 3½ years.

To all whom it may concern:

Be it known that I, MAX N. AARON, a citizen of the United States, residing in Philadelphia, county of Philadelphia, and State of Pennsylvania, have invented a new, original, and ornamental Design for a Lace Trimming, of which the following is a specification, reference being had to the accompanying drawing, which forms a part thereof.

The figure is a plan view of a number of repeats of a trimming embodying my design. The same comprises a succession of figures composed of relatively thick thread

with a network background of relatively thin thread, the threads being arranged and the figures shaped to produce the appearance shown in the drawing.

I claim—

The ornamental design for a lace trimming, as shown and described.

In testimony of which invention, I have hereunto set my hand, at Philadelphia, on this 2nd day of May, A. D. 1917.

MAX N. AARON.
